UNITED STATES PATENT OFFICE

GEORGE B. BEAMAN, OF CRAFTON, PENNSYLVANIA, ASSIGNOR TO SUPERIOR PAPER PRODUCTS COMPANY, OF CARNEGIE, PENNSYLVANIA, A CORPORATION OF DELAWARE

SPACING PAD

Application filed June 12, 1930. Serial No. 460,634.

This invention relates to spacing pad members made from corrugated paper, for use in shipping containers, to protect articles packed therein against injury in shipment.

The object of the invention is to provide a spacing pad member that is light, strong, and dependable, readily adapted to pack various forms of articles by spacing them apart and/or form a container, simple and inexpensive to manufacture, and sufficiently resilient and strong to absorb the shocks to which an article packed in a container is ordinarily subjected in shipment or handling.

A further object is to provide a packing pad that may be made in a variety of forms of a single strip of corrugated paper folded upon itself, and bound into final shape by adhesive tape, glue, staples, or the like, which will provide spacing in two or more directions.

As is well known, the packaging of fragile or surface-finished articles for shipment or carriage is expensive. Paper, excelsior, straw, etc., as ordinarily used involve much waste, and frequently fail in their intended function. The present invention is directed to providing a packing pad that may be used at certain essential points, leaving large free spaces at other points. Unfilled air space between articles and containers is cheaper than any other packing, provided the article is sufficiently protected otherwise. By making the spacing pads of corrugated paper, which is a material of maximum strength per unit of weight, and particularly by building up thickness by folding such paper on itself, I provide packing pads that have strength comparable to that of soft wood blocks, but much lighter, and of greater resiliency and cushioning effect.

These and other objects, as well as various other features of the invention, will be more apparent when the following detailed description is read in conjunction with the accompanying drawings, of which Figs. 1 to 9, inclusive, illustrate forms of spacing pad members constructed of corrugated paper; Fig. 10 is a sectional view of a shipping container encasing, for example, a glass cylinder, of the type employed in gasoline dis-

pensing pumps, two forms of spacing members embodying the invention being shown as employed to protect the cylinder against injury; Fig. 11 is a plan view showing a circular article such as a plate or phonograph record resting on spacing members disposed in the bottom of a container; and Figs. 12 and 13 are a longitudinal partial section, and a transverse sectional view, respectively, of a package containing a burial casket, in which pads of corrugated paper of various forms are employed for protecting the casket against injury in shipment, by spacing it from the shipping box.

In practicing the invention, sheets of corrugated paper are cut into strips having the correct length and width to form spacing pad members of desired size and shape. The strips are scored or creased at spaced intervals, preferably at right angles to the length of the strip, to permit the folding of the strip upon itself to the form desired. After the folding and shaping is completed, the resultant pad is bound in permanent form by some suitable means, such as glue, or preferably adhesive tape around the folded portion. Staples may also be used through the folded portion, but their use is not always desirable, as the staples may scratch articles contacting therewith.

In Fig. 1 the pads are bound and retained in form by glue 3 applied at spots near the edges of the folded portion, while in Fig. 2, binding by the use of staples 30 is shown.

Spacing pad members embodying the invention may be made in a number of different forms by folding the strips in various manners. One of the simplest forms is illustrated in Fig. 6, where a strip 1 of corrugated paper is lapped back and forth upon itself a number of times and then the end of the strip carried entirely around the folded portion, forming a continuous casing around its four sides. To hold the pad in permanent form adhesive tape 2 is preferably used, the tape being extended around the edges and over the member sufficiently to adequately bind the folds of corrugated paper together. While the pad may be made by folding the strip in zig-zag fashion as shown in Fig. 6,

for example, it may also be formed as shown in Fig. 5, where the body of each pad section is made by folding the strip around its end in helical fashion, and then binding the folded portion together with tape 2. That figure also shows a combination of two spaced pads with a flexible connection forming a spacer and retaining notch between.

In Figs. 1, 2, 3, and 4, there are shown a plurality of modifications of the invention, in which the folding is done in a number of different ways.

The spacing member shown in Fig. 1, comprises two sections so formed that when folded to the L-shape illustrated the inner end or edge of one pad engages and seats on the side wall of the other pad.

In Fig. 2 a pad having two sections quite similar to that shown in Fig. 1, is shown, differing only in that the strip is carried around the inner side of the perpendicularly disposed pad instead of the back, and hence the horizontal leg pivots at the inner edge of the perpendicular member rather than at the outer edge.

In Fig. 4 an arrangement is employed wherein the folds of the strip forming two sections are made at right angles to the leg section of the member.

In Fig. 3 a packing member is shown having a long pad body with supplementary leg pads at each end. The intermediate body section is reinforced by a separate section consisting of a strip of corrugated paper folded upon itself and bound by strips of adhesive tape to the part of the main strip connecting the two end pads together.

In Fig. 5 there is illustrated a form of packing member adapted more particularly for packing disc or plate-like articles, such as phonograph records, mirrors, plates, or the like. It consists of two pad sections formed by winding the ends of a strip of corrugated paper upon themselves in helical fashion. The pad sections at each end of the strip are spaced from each other by a portion of the strip which is folded inwardly upon itself at 4 to engage the faces of the pads 5 and 6. By this construction a space 7 is provided in which the plate-like articles to be packed may be inserted, and the pad sections are positively spaced apart by the folded intermediate portion of the strip.

In Fig. 10 there is illustrated a shipping package comprising a rectangular box or container 8, in which a glass cylinder 9 is arranged and protected by a number of pad members 11 and 12. The ends of the cylinder 9 are spaced from the side and end walls of the container 8 by means of the L-shape packing members 11, constructed as shown in Figs. 1, 2 or 4. One leg or section of the pad lies between the cylinder and end wall of the box, and the other between the cylinder and side wall. The pads are maintained in

place at the middle of the side walls of the box by a flat spacing member 13 illustrated more clearly in Fig. 11. This spacing member is made of corrugated paper also, and is provided with cut outs 14, adapted to receive one leg of each of the spacing members 11, and to rest on top of the other legs thereof.

In the middle of the cylinder a plurality of pad members of the type illustrated in Fig. 5, may be used. These intermediate packing members may be held in place by being bound by glue or other suitable means to the side of the container, or they may be held in place by a member 16, similar to the spacing member 13, except that a hole is cut in its center to permit the cylinder 9 to slide through it when it is placed in the container 8.

Figs. 7, 8 and 9 show a number of other forms in which spacing pad members may be constructed. For example such pads are adapted for use in connection with the packaging of a burial casket as illustrated in Figs. 12 and 13.

The casket 17 is arranged in a container 18 and the casket is spaced from the end and side walls thereof by pad members. At the ends, pad members are used comprising a web 19 connecting folded end sections 21, spaced from each other sufficiently to permit their engaging the projecting edge portions 22 and 23 of the casket. The space between the pad sections 21 may be varied to conform to different shapes of caskets or other objects packed in this manner. This spacing is adapted to provide clearance for the handles mounted on the exterior of the casket. Where the casket has a tapered wall the lower portion 25 of the pad member may be made in a triangular form as shown in Fig. 7. The packing members may be made in separate sections, as shown in Fig. 9, and attached to the walls of the packing case in fixed position by glue.

One advantage of the pads made up as described resides in the simplicity and inexpensive manner in which packing members of this type may be produced and the easy manner in which they may be applied to an article, as well as the easy manner in which they may be adapted for different shapes and forms of articles. By creasing and folding a single strip of corrugated paper in the manner described above, it is possible to produce a spacing member of great strength and light weight and which is not likely to get out of shape or be displaced in use.

It has been found in practice that spacing members of this form may be used at considerable saving of cost of material, and labor of packing, and that the articles are amply protected while the weight of the completed package is greatly reduced.

According to the provisions of the patent statutes, I have explained the principles and

mode of operation of my invention and have illustrated and described what I now consider to represent its best embodiment. However, I desire to have it understood that with-
5 in the scope of the appended claims the in-
vention may be practiced otherwise than as specifically illustrated and described.

I claim:

1. A packing pad or spacing member for use at spaced points about the walls of a shipping container, comprising a continuous strip of corrugated paper creased at spaced intervals and tightly folded upon itself a plurality of times along said creases to form a single compact resilient pad of rectangular shape, and means binding said folds together to maintain the structure in a predetermined shape.
- 10 2. A spacing member adapted for use at spaced points about the ends of a shipping container, comprising a sheet of corrugated paper tightly folded upon itself a plurality of times at its ends to form two connected resilient compact pad sections, said sections being arranged at right angles to each other to form a single L-shaped pad member.
- 15 3. The combination with the spacing pad of claim 2, of a positioning member having cut-out portions adapted to receive one leg of said pad members and to rest upon the other leg, whereby to hold the pads in position relative to a container wall.
- 20 4. A packing pad or spacing member for use at spaced points about the ends of a shipping container, comprising a strip of corrugated paper tightly folded upon itself a plurality of times at each end in a manner to form two separate connected compact resilient pads, the intermediate portion of the strip being creased and bent to bring one pad into edge contact with the face of the other pad, whereby to produce a unitary L-shaped spacing pad.
- 25 5. A spacing member adapted for use in shipping containers, comprising a sheet of corrugated paper creased at spaced intervals and folded upon itself along said creases a plurality of times at its ends to form two spaced resilient packing sections, one being in the form of a tightly folded compact rectangular block and the other in the form of a right triangle.
- 30 6. A spacing member adapted for use in shipping containers, comprising a strip of corrugated paper tightly folded upon itself a plurality of times at each end in such manner as to form two connected resilient pad sections, the strip intermediate said sections being folded upon itself to provide a space between the pad sections for the reception of means for holding the pad in place in a shipping container.

In testimony whereof, I sign my name.
GEORGE B. BEAMAN.
